DESIGN FOR A PITCHER OR SIMILAR ARTICLE

Francis Leonard Thorley, Stoke-on-Trent, England, assignor to Copeland & Thompson, Inc., New York, N. Y., a corporation of New York

Application August 20, 1941, Serial No. 102,962
In Great Britain March 27, 1941

Term of patent 3½ years

To all whom it may concern:

Be it known that I, Francis Leonard Thorley, a subject of the King of Great Britain, residing at Grindley House Blythe Bridge, in the City of Stoke-on-Trent, England, have invented a new, original, and ornamental Design for Pitchers or Similar Articles, of which the following is a specification, reference being had to the accompanying drawing, forming part thereof.

Figure 1 is an elevation of one side, and Figure 2 is an elevation of the other side, of a pitcher showing my new design.

I claim:

The ornamental design for a pitcher or similar article, as shown.

FRANCIS LEONARD THORLEY.
